UNITED STATES PATENT OFFICE.

WILLIAM H. GUPPY, OF PHILADELPHIA, PENNSYLVANIA.

GUARD-RAIL.

No. 833,685.

Specification of Letters Patent.

Patented Oct. 16, 1906.

Application filed June 23, 1906. Serial No. 323,020.

To all whom it may concern:

Be it known that I, WILLIAM H. GUPPY, a citizen of the United States, residing at Philadelphia, in the county of Philadelphia, 5 and State of Pennsylvania, have invented certain new and useful Improvements in Guard-Rails, of which the following is a specification.

The invention to be hereinafter described relates to guard-rails for railroads, and more particularly to such rails as are employed at railroad switches, crossings, and the like.

As is well known, such guard-rails are placed at desired points in the rail system parallel to the main rail to receive between it and the main rail the flange of the passing wheels, to thereby prevent any lateral or side movement of the truck. In order that such guard-rail shall properly perform its function, 15 it is desirable that it be placed sufficiently close to the main rail that the flange of the passing wheel, by contacting with the guard-rail, shall prevent the tread-surface of the wheel from leaving the main rail. Likewise, 20 to insure the proper passage of the flange between the main and guard rails as the wheel approaches the guarded point the ends of the guard-rail are bent away from the main rail.

Guard-rails as now commonly constructed are formed from the ordinary standard rail, the ends being bent as described, and in order to secure its desired close relation to the main rail, the flange of the guard-rail opposite that 25 toward which the ends are bent is planed or cut off to the desired extent. This is not only an expensive structural formation but weakens the rail at the parts most subjected to strain and forms a line of weakness at the 30 union of the bends with the main body of the rail by such removal of material.

With these general considerations in view the object of the present invention is to provide a guard-rail which shall be not only 35 economical in construction, but wherein the desired strength shall be maintained and lines of weakness avoided.

The invention consists of the structure to be hereinafter described and then definitely 40 pointed out in the claims.

In the drawings, Figure 1 is a plan view of a main and guard rail secured to the ties on which they rest. Fig. 2 is a plan view of the guard-rail, showing the rolled flange at one

side thereof of less width than the flange on 55 the other side and with the metal of the flange rolled or drawn toward the bent ends of the rail. Fig. 3 is a cross-section of the main and guard rails on line x x , Fig. 1, showing the wheel-flange between the two; 60 and Fig. 4 is a perspective view of the end of the guard-rail, showing in a somewhat distorted way the metal rolled or drawn toward that point.

In the drawings, A represents the main rail 65 of the usual track system, said rail being secured to the ties B by the usual spikes a. Disposed adjacent to the main rail A is the guard-rail D, which is preferably formed from the usual or standard rail, such as that 70 represented by A, as will hereinafter appear.

In order that the guard-rail D may be fitted sufficiently close to the main rail A, it is necessary that one of its flanges be reduced in width, such reduction heretofore being secured by cutting or planing off this flange to the desired extent. This planing or cutting off of the flange of the guard-rail is not only 75 an expensive and laborious operation, but it weakens the rail, especially near the points 80 where the ends of the rail are bent, as shown in Figs. 1 and 2. In the present invention the flange d^3 of the guard-rail, which is to be next to the main rail, is reduced in width by 85 rolling said flange and drawing the metal of said flange toward the bent ends d of the guard-rail. This drawing of the metal toward the ends of the guard-rail maintains the full strength of the rail at the bent portions and supplies the metal at these points, 90 which is necessary at the exterior contour of the curve or at the points d .

By reference to Figs. 1 and 2 it will be noted that the flange d^2 of the guard-rail D is of the usual or standard width and that the 95 flange d^3 is of reduced width, the surplus metal in the flange d^3 being drawn toward the end of said flange at d , as shown in Figs. 2 and 4.

The structural formation of the guard-rail 100 by drawing the metal toward the ends thereof where the guard-rail is bent prevents lines of weakness at the bent contour near the ends, and economy of production results.

As is well understood, the guard-rail and 105 main rail receive between them the flange C, Fig. 3, of the passing wheel, and the ends of the guard-rail are bent, as shown, so as to re-

- ceive and direct the flange C of the wheel into its proper relation with the main and guard rail. Obviously if the flange C strikes the guard-rail near the bent end portion sufficient strength must be present in the guard-rail to resist the blow, and this is furnished by the surplus metal of the flange d^3 being drawn toward the end of the rail, as hereinbefore described.
- 10 The guard-rail is secured in position by means of the spikes or bolts b , which are connected with the usual ties B.
- Having thus described my invention, what I claim, and desire to secure by Letters Patent, is—
- 15 1. A guard-rail having one of its flanges

decreased in lateral extension, the surplus metal of said flange being distributed toward the ends of the rail.

2. A guard-rail having the ends thereof turned in the same direction, the flange on the side thereof opposite that to which the ends are turned, having the surplus metal drawn and distributed toward the ends of the rail.

In testimony whereof I affix my signature in presence of two witnesses.

WILLIAM H. GUPPY.
